N. Y.

Application August 6, 1949, Serial No. 4,344

Term of patent 14 years

(Cl. D35—3)

To all whom it may concern:

Be it known that we, Alex Zwierzynski and Jacob Abel, citizens of the United States of America, residing, respectively, at the Borough of the Bronx, in the county of the Bronx and State of New York and the Borough of Queens, in the county of Queens and State of New York, have invented a new, original, and ornamental Design for a Christmas Tree Stand or Similar Article, of which the following is a specification, reference being had to the accompanying drawing, forming part thereof.

In the drawing

Fig. 1 is a front elevational view of a Christmas tree stand or similar article, showing our new design; and

Fig. 2 is a top plan view thereof.

The dominant features of our design reside in the portions shown in full lines.

We claim:

The ornamental design for a Christmas tree stand or similar article, substantially as shown and described.

JACOB ABEL,
ALEX ZWIERZYNSKI.
